UNITED STATES PATENT OFFICE

158,139

COMBINED TOOTHBRUSH AND TUMBLER
HOLDER

Paul F. Simpson, Washington, Conn., assignor to
The Autoyre Company, Inc., Oakville, Conn., a corporation of Connecticut
Application February 24, 1949, Serial No. 1,067

Term of patent 14 years

(Cl. D4—3)

To all whom it may concern:

Be it known that I, Paul F. Simpson, a citizen of the United States, residing in Washington, State of Connecticut, have invented a new, original, and ornamental Design for Combined Tooth Brush and Tumbler Holder, of which the following is a specification, reference being had to the accompanying drawing, forming a part thereof.

Fig. 1 is a perspective view of a combined tooth brush and tumbler holder, illustrating my new design, the said view also illustrating a bracket in dotted lines;

Fig. 2 is a plan view of the combined tooth brush and tumbler holder of Fig. 1, and

Fig. 3 is a side view of the design of Fig. 1.

The dominant features of my new design are illustrated in the drawing in full lines.

I claim:

The ornamental design for a combined tooth brush and tumbler holder, substantially as shown and described.

PAUL F. SIMPSON.
